INVENTOR.
Cloise H. Baldwin.

Wise H. Baldwin,

BY
Geo. F. Kimmel, ATTORNEY.

UNITED STATES PATENT OFFICE.

CLOISE H. BALDWIN, OF FORT WORTH, TEXAS.

PUMP JACK.

Application filed December 6, 1927. Serial No. 238,175.

This invention relates to a new and improved pump jack assembly, and has for its object to provide, in a manner as hereinafter set forth, an assembly of such class constituting a single self contained unit thereby simplifying construction and installation and further materially reducing the cost of the maintenance over forms of pump jack assemblies now in use.

10 A further object of the invention is to provide, in a manner as hereinafter set forth, a pump jack assembly including means for producing at all times an absolutely vertical pumping stroke.

15 A further object of the invention is to provide, in a manner as hereinafter set forth a pump jack assembly including an oscillatory beam and with means to prevent the sagging or distortion thereof during its operation.

20 Further objects of the invention are to provide, in a manner as hereinafter set forth a pump jack assembly which is comparatively simple in its construction and arrangement, strong, durable, compact, thoroughly efficient 25 in its use, readily assembled, conveniently installed and comparatively inexpensive to set up.

With the foregoing and other objects in view the invention consists of the novel construction, combination and arrangement of parts as hereinafter more specifically described and illustrated in the accompanying drawings wherein is shown an embodiment of the invention, but it is to be understood that 30 changes, variations and modifications can be resorted to which fall within the scope of the claims hereunto appended.

In the drawings wherein like reference characters denote corresponding parts throughout the several views:

Figure 1 is a side elevation, of a pump jack assembly in accordance with this invention, showing the adaptation thereof with respect to a well casing.

45 Figure 2 is a section on line 2—2 Figure 1. Figure 3 is a section on line 3—3 Figure 1. Figure 4 is a section on line 4—4 Figure 2. Figure 5 is a section on line 5—5 Figure 2. Figure 6 is a top plan view of a base plate.

50 Figure 7 is a side elevation of the bearing element for the oscillatory swing.

Figure 8 is a section on line 8—8 Figure 1.

Figure 9 is a section on line 9—9 Figure 1.

Figure 10 is a section on line 10—10 Figure 3.

Figure 11 is a side elevation of the coupling yoke for the beam.

Figure 12 is a fragmentary view in side elevation of the Samson post.

Figure 13 is a section on line 13—13 Figure 8.

The assembly includes a Samson post comprising a pair of oppositely disposed standards 7, 8, preferably in the form of channel irons and each having the major portion 65 thereof outwardly inclined as at 7' and its remaining portion perpendicular as at 8'. The perpendicular portions 8' of the standards are arranged at the upper ends thereof. The channels of the standards are disposed outwardly. The standards at their lower ends are connected together by a pivotally mounted base, generally indicated at 9 and which permits of the oscillating of the post.

The base 9 is formed of a hollow casting 10 75 provided at each end with bearings 11 for a pivot bolt 12, and the latter extends through and projects from each end of the casting 10. Near each end of the top of the casting 10 a lubricant well 13 is provided and leading 80 therefrom to the bolt 12 is a lubricant supply port 14. At each end of the casting 10 is an upwardly extending and inwardly inclined arm 15, which extends into the lower end of

85 the channel of a standard and is fixedly secured therewith by a plurality of holdfast devices 16 whereby the standards are connected together at their lower ends with the casting 10 disposed below said ends. At each end of each side of the casting 10 is a 90 laterally extending and upwardly inclined apertured ear. The ears at one side of the casting 10, are indicated at 17 and those on the other side at 18. The function of the apertured ears will be presently referred to.

95 At each end of the bottom of the casting 10 is a depending curved lug 19 providing means for spacing the major portion of the casting from the main base of the assembly. The casting 10 is of inverted U-shape in vertical 100 section and the arms 15 are of greater width than the width of the casting, and the lugs 19 also form fulcrums for the latter. Mounted in the casting 10 is a removable bearing sleeve

105 19' for the bolt 12.

The main base of the assembly consists of a pair of parallel, spaced I-beams 20 of appropriate length and secured against the outer face of the web of each beam in proximity to one end of the latter, by the holdfast de-

vices 21 is a combined coupling and supporting member 22 for the pivot bolt 12. The upper part of each member 22 is offset as at 23, projects above the head of each beam and 5 opposes the lower end of an arm 15. The bolt 12 is threaded at each end and extends through and projects from each offset portion 23. Carried on the projecting ends of the bolt 12 are securing nuts 24.

10 Arranged between the standards 7, 8 at the perpendicular portions 8', are bearing elements, each formed of a plate 25 provided on its inner face, near its upper end with a circular boss 26, and below, as well as spaced 15 from the flange 26, with an inwardly disposed tubular extension 27 providing a bearing. On the top of each extension is a lubricant well 28 and leading therefrom to the interior of the extension is a lubricant supply port 29.

20 The plates 25 are of less length than the length of the perpendicular portion 8', and have their upper ends flush with the upper ends of the portions 8'. The plates 25 are arranged in opposed, spaced relation, and are 25 secured by holdfast devices 30 against the inner faces of the portions 8' of the standards. Mounted at its ends upon the circular bosses 26 is a combined spacing and bracing member 31 of tubular form which abuts against 30 the inner faces of the plates 25. The member 31 forms a lubricant reservoir 33' having outlets 33'' in its bottom for supplying lubricant to the wells 28.

35 Journaled in the bearings formed by the extensions 27 is a trunnion element 32 for the oscillatory beam, to be presently referred to, for the pump rod, also to be hereinafter referred to. The trunnion element 32 is of 40 T-shaped form and has its stem 34' secured to the oscillatory beam eccentrically thereof.

45 Secured within the channel of each standard a substantial distance above the lower end thereof, as well as projecting from each side of the standard is a coupling member 28' formed with a pair of oppositely extending apertured ears 29'. The holdfast means for the coupling members 28' are indicated at 30'. One pair of ears 28' associated with the ears 17 and the other pair with the ears 18. Connected to the pairs of associated ears is a pair 50 of oppositely extending reinforcing bars 31' for the post. The bars 31' extend through the apertures in the ears and carry securing nuts 32' on their ends and which abut against 55 the outer faces of the ears.

60 The oscillatory beam is referred to generally at A and consists of a pair of oppositely disposed, spaced, parallel channel irons 33, 34, having the flanges thereof directed outwardly. The trunnion element 32 has its stem 34' extended between the irons 33, 34, and is secured to these latter by the holdfast device 34'' and is positioned between the transverse median of the beam A and the rear 65 end thereof.

The rear end of the beam A, has depending therefrom, a counterweight 36. The channel bars or members of the beam A at the forward terminal portion thereof have spaced openings 37, 38 and 39 and the openings in one 70 channel bar align with the openings in the other channel bar. The openings 37, 38 provide means for adjustably connecting a casting 40 between the channel bars 33, 34 rearwardly of the openings 39. The casting 40 provides 75 a lubricant reservoir and said casting 40 depends below the beam A and is formed with a globular portion 41 which extends from the bottom thereof. The globular portion 41 contacts with a concave cup 42 connected to the 80 upper end of an actuating arm 43 which will be hereinafter referred to. The elements 40, 41 and 42 are constructed in a manner as disclosed in my application Serial No. 168,076, filed February 14, 1927.

85 The top flanges of the I-beams 20 are formed with openings 44 to provide for adjustably connecting thereon a base or supporting plate 45, by the holdfast devices 46. The ends of the plate 45, at each corner thereof is 90 formed with an opening 45' for the passage of a holdfast device 46. The plate 45 is also formed with two spaced pairs of transversely extending slots 47. The slots of each pair are disposed in lengthwise arrangement relative to each other and also in spaced relation. The lower face of the plate 45 in proximity to each end is formed with a transversely extending 95 shoulder 48 which abuts against the inner side edge, at the top of an I-beam 20. Formed integral with the upper face of the plate 45, centrally thereof, at its rear side is a holding lug 49 including a vertical and a horizontal leg and with the latter extending forwardly from the upper end of the latter.

100 Mounted on these holdfast devices 46, which extend through the forward openings 45' are spacing collars 50 for the apertured rear ends of a pair of adjusting rods 51 which project forwardly from the plate 45, and extend through upstanding flanges 51' formed at the rear ends of a pair of longitudinal extensions 51'' which project rearwardly from a substantially V-shaped well casing retaining member or element 52.

105 The extensions 51'' are provided with oppositely disposed flanges 53 which overlap the heads of the I-beams 20, see Figure 4, whereby the member 52 is slidably connected to said beams. The securing nuts 54 of the forward holdfast devices 46 clamp against the apertured rear ends of the rods 51 and through said ends extend the bolts of said forward holdfast devices 46. The member 52 surrounds and abuts against the well casing or tubing 54'.

110 Carried by each of the rods 51 and threadably engaging the forward terminal portions thereof are clamping nuts 55 for maintaining the retaining member 52 in adjusted position.

The retaining member 52 can be adjusted rearwardly and forwardly with respect to the beams 20 for the purpose of retaining the well casing or tubing 54' in the desired position 5 and further for retaining the casing 54' relative to the pump rod 96 so that the stroke of the latter will be absolutely vertical relative to the casing or tubing 54'.

Secured to each of the beams 20 and against 10 the outer face thereof are upstanding coupling pieces 57. The securing means for the coupling pieces 57, consists of bolts 58, each carrying clamping nuts 59. The coupling pieces 57 having offset upper portions 57' provided with openings 57" through which pass headed bolts 58' carrying retaining plates 59' and securing nuts 60. The coupling pieces 57 are positioned at the rear of the plate 45, project upwardly therefrom and 20 the offset portions 57' extend slightly above the bearings 57".

Depending from the beam A, is a tapered supporting yoke 61, having spacing lugs 61' at its top for the channel irons 33, 34. The lugs 61' abut the inner faces of the irons. The yoke 61 has the lower portion of each side thereof straight, as at 62, and secured to the outer face of each portion 62 is a casting 63 formed with a tubular extension 64 providing 30 a bearing. Holdfast devices 65 and 66 secure a casting 63 to each portion 62 of the yoke. Retaining plates 67 are carried at the outer ends of the holdfast devices 66. Mounted on each bearing 64 is an adjustable sectional block 68 formed with a pair of openings 69 extending from the top to the bottom of the block. Mounted on the bolts 58' are bearing blocks 70 having a pair of oppositely extending apertured ears 71 at the top thereof. 40 Within each block 70 is arranged a liner 70'. See Figure 13. The liner 70' is provided at its top with a lug 70" formed with a seat 71' into which extends a pressure exerting means consisting of a pin 71" which depends from 45 a plate 72' mounted on the reduced, threaded lower terminals 72" of the rods 72. The reduced terminals 72" provide shoulders 72''' which abut the plate 72'. Each block 70 is formed with an opening 70''' for the pin 71". 50 and also with a recess 73' for the lug 70". On rotation of the rods 72, in one direction, plate 72' will cause movement of the pin 71" to exert pressure on the liner 70'. An adjustable block 68 associates with a bearing block 70 and is connected therewith by a pair 55 of rods 72 having their upper ends clamped to the block 68, by the nuts 73, and their lower ends clamped to the ears 71 of the block 70 by the nuts 74. The nuts 73 adjustably connect the sections of each block 69 together. Secured to the sides of the yoke 61, as at 75 are forwardly and rearwardly extending inclined 60 brace members 76, 77 respectively, which have their upper ends secured to the beam A. The

members 76 are arranged forwardly of the 65 Samson post and the members 77 extending through and rearwardly thereof. The elements 61, 70, 76 and 77 act as a pivoted truss or reinforcement for the beam A and prevents the sagging or distortion thereof during its 70 oscillations.

Arranged over the beams 20, and forwardly with respect to the standards 7, 8 is an oscillatory swing referred to generally by the reference character B and which includes a 75 horizontally disposed arm 77' and a vertically disposed arm 76' and with the latter of less length than the former. The arms 76', 77' are connected together by brace members 78. The swing B is constructed in a manner as 80 set forth in my application Serial No. 168-076, filed February 14, 1927. Secured to the arm 76' at a point between its transverse median and its rear end is a casting 79, formed with an inverted T-shaped extension 85 80 which depends therefrom and has its lower end mounted in the concavity 81 of a bearing member 82 mounted on the plate 45. Holdfast devices 84 and 85 extend down through the front and rear of the bearing member 82 90 and through the slots 47 of the plate 45. The bearing member 82, has a rearwardly extending flange 86 which is overlapped by the holding lug 49, see Figure 5. Secured to the arm 76', at the outer end thereof, is a casting 95 87, which provides a bearing for a trunnion member 88, fixed to the lower end of the actuating arm 43. The castings 79 and 87 are constructed in the same manner as disclosed in my application aforesaid. The arm 77' 100 at its upper end is provided with a stirrup box 89, formed with a plurality of grooves 90 for selectively receiving a stirrup 91 which is connected by the coupling 92, to the pull rod 93. The stirrup box 89 is constructed in 105 the same manner as disclosed in my application aforesaid.

Connected with the forward end of the beam A by a holdfast device 94 extending through the registering openings 39 is a casting 110 95 which is employed for connecting the pump rod 96 to the beam A. The casting 95 is constructed in the same manner as that disclosed in my application aforesaid.

The straight line effect of the pumping rod 115 96 is produced by direct connection of the beam A to any rigid part of base or frame between the well and the standards 7 or 8, in such a manner that desired adjustments or change of positions of the elements 40, 80, 89, 120 51 and 82, will not in any manner influence or limit the ability of the bearing element 97 which is carried by the pump rod 96 to produce at all times an absolutely vertical pumping stroke.

It is thought the many advantages of a pump rod assembly, in accordance with this invention can be readily understood, and al-

though the preferred embodiment of the invention is as illustrated and described, yet it is to be understood that changes in the details of construction can be had which will fall within the scope of the invention as claimed.

What I claim is:

1. In a pump rod assembly, supporting means, a swing element bearing adjustably connected therewith, and a coupling connection attached to said bearing, slidably connected with said means and further provided with means for connecting it with a well casing, said coupling connection being adjustable.
15. 2. In a pump rod assembly, supporting means, a swing element bearing carried thereby, and a coupling mechanism attached at one end to said bearing, slidably connected intermediate its ends to said means and further having its outer end provided with means for connecting it to a well tubing.
20. 3. In a pump rod assembly, supporting means, a swing element bearing mounted thereon, a coupling mechanism attached at one end to said bearing, slidably connected intermediate its ends to said supporting means and further having its outer end provided with means for connecting it to a well tubing, an oscillatory beam for operating the pump

rod, a truss connection between said supporting means and said beam.

4. In a pump rod assembly, supporting means, a swing element bearing adjustably connected therewith a coupling connection attached to said bearing, slidably connected with said means and further provided with means for connecting it with a well casing, said coupling connection being adjustable, an oscillatory beam for operating the pump rod, and a truss connection between said supporting means and said beam.

5. In a pump rod assembly, an oscillatory beam for operating the rod, supporting means for the beam, a base for said means, a truss connection between the base and beam, said truss connection having its top arranged forwardly and rearwardly of said means.

6. In a pump rod assembly, an oscillatory beam for operating the rod, supporting means for the beam, a base for said means, a truss connection between the base and beam, said truss connection having its top arranged forwardly and rearwardly of said means, and pivoted intermediate its ends.

In testimony whereof, I affix my signature hereto.

CLOISE H. BALDWIN.
